UNITED STATES PATENT OFFICE.

GEORGE SHAW, OF LEEDS, ENGLAND.

SPINNING-FRAME FOR FLAX, HEMP, JUTE, AND OTHER FIBERS.

1,183,776.

Specification of Letters Patent.

Patented May 16, 1916.

Application filed March 14, 1913. Serial No. 754,342.

To all whom it may concern:

Be it known that I, GEORGE SHAW, a British subject, residing at Leeds, county of York, England, have invented certain new and useful Improvements in Spinning-Frames for Flax, Hemp, Jute, and other Fibers, of which the following is a specification.

This invention relates to machines for spinning flax, hemp, jute and similar fibers to which a cop or bobbin building motion is applied. It is customary in these machines to raise the bobbin building rail by a cam acting through a long connecting chain and link to rotate the lifting shaft in one direction, but to allow the rail to fall by its own excess weight.

The object of this invention is to mount the cam and a rack in such a way as to operate or rotate the lifting shaft in both directions and thereby completely control the movement of the builder rail in both the upward and downward direction and by this means to obtain a quick traverse and a cross wind of the yarn on the bobbin.

The invention consists essentially in arranging the building cam to act directly on a sliding rack to move it positively in both directions, which rack in turn meshes directly with a pinion on the lifting shaft of the machine to rotate it first in one direction and then in the reverse direction to impart a positive motion both up and down to the spindle rail.

The invention will be fully described with reference to the accompanying drawings.

Figure 1. is a transverse sectional elevation of part of a revolving ring and centrifugal presser spinning frame having the invention applied thereto. Fig. 2. is a part end elevation of same. Fig. 3. is a sectional plan at one end of the machine.

The machine illustrated is of the newest type of construction for jute spinning with drawing rollers A, revolving ring B, centrifugal presser b, spindle C and vertically reciprocating spindle rail D, said rail being raised by vertical racks E meshing with pinions e placed at intervals on the lifting shaft F of the machine. The invention is, however, applicable to other ordinary types of spinning frames.

On one end of the lifting shaft F a second pinion G is affixed, with which a reciprocating sliding rack H meshes to give a

reciprocating rotary movement to the lifting shaft F.

The reciprocating sliding rack H is preferably placed horizontal and is mounted in a guide casing h in the framing at one end 60 of the machine; the said casing completely inclosing the rack, as will be understood from Figs. 2 and 3. The teeth of the reciprocating sliding rack H mesh with the pinion G on the lifting shaft F. To the 65 reciprocating rack H two rollers h¹ and h² are fitted on studs h³ secured to the rack and project laterally from the same through slots formed in the inner side of the casing h. The lifting cam K is mounted to rotate between the two rollers h¹ and h² and is in contact with both to impart movement to the rack H first in one direction and then in the reverse direction. By this means a double-acting movement is imparted to the rack and 75 by it to the spindles, which movement is sensitive and positive in both directions.

The cam K is driven at a suitable speed from the front delivery roller of the machine, or from any other convenient part by gear k. It is of heart or other shape to give 80 a similar movement to the rack H, in both directions and shaped to prevent a dwell of the rack at either end. The rollers h¹ and h² with which the cam contacts are mounted 85 on studs h³ which are readily adjusted to maintain them in close contact with the periphery of the cam.

I preferably suspend balanced weights W to the lifter shaft to about counterbalance 90 the weight of the spindle rails.

By this arrangement I am able to impart a long lift to the builder rails, and to drive same at a quick up and down speed, so as to produce a cross wound bobbin, and one 95 which may be spun on the bare spindle, or on paper tubes, or on headless wooden bobbins.

What I claim as my invention and desire to protect by Letters Patent is:—

1. In a spinning frame, the combination with a vertical spindle, a rail carried thereby, a reciprocatory vertical rack bar to which the rail is directly connected, a horizontal lifting shaft and a lifting pinion 105 thereon meshing with the vertical rack bar to impart a positive movement in opposite directions to the rack spindle and rail, of a second pinion fixed to the horizontal shaft, a horizontal casing, a second rack bar com- 110

pletely housed in said casing and movable in a horizontal plane therein, one end of said second rack bar meshing with the other of said pinions, spaced rollers laterally extending from said second rack bar at its opposite end, a cam member interposed between and in engagement with said rollers for imparting an endwise reciprocatory movement to said second rack bar, and driving means for said cam.

2. In a spinning frame, and in combination, a vertical spindle, a rail carried thereby, a vertically reciprocatory rack bar to which said rail is directly connected, a horizontally reciprocatory rack bar, pinions having a stationary axis and meshing with said

rack bars whereby the vertical rack bar is reciprocated, guide means for said horizontally reciprocatory bar comprising a horizontally extending casing having its inner side wall longitudinally slotted, means for actuating said horizontally reciprocatory bar and means extending from said last-mentioned bar and in constant engagement with said actuating means.
